UNITED STATES PATENT OFFICE.

FRANK M. LEAVITT, OF BROOKLYN, NEW YORK, ASSIGNOR TO THE E. W. BLISS COMPANY, OF SAME PLACE.

DROP-HAMMER.

SPECIFICATION forming part of Letters Patent No. 350,007, dated September 28, 1886.

Application filed April 22, 1886. Serial No. 199,872. (No model.)

To all whom it may concern:

Be it known that I, FRANK M. LEAVITT, a citizen of the United States, residing at the city of Brooklyn, county of Kings, and State 5 of New York, have invented an Improvement in Drop-Hammers or Drop-Presses; and I do hereby declare that the following is a full, clear, and exact description of the same, reference being had to the accompanying drawings, forming 10 part of this specification.

The invention relates to that type of drop-hammers or drop-presses in which the hammer or weight which is first raised and then dropped to strike the required blow by expenditure of the living force acquired during 15 its fall is lifted by means of a flexible band or strap engaged by clamping friction-pulleys when the weight is being lifted and released from such engagement when the hammer or 20 weight has been raised.

The principal objects of my present invention are to prevent the band or strap from wearing, as has heretofore been the case, by the action of friction upon the pulleys during 25 the falling of the weight, and to obviate the resistance to the fall of the weight due to such action of friction between the pulleys and strap or band, and thus secure a more free and effective fall of the weight, whereby an 30 equally effective blow can be secured with a lighter hammer or a more effective blow from a hammer of the weight hitherto employed. A collateral purpose is also economy of power in driving this class of machines.

35 The construction and operation of my invention will fully appear from the following description and the drawings, of which—

Figure 1 is a front view with a medial portion broken out to permit essential parts of 40 the machine to be presented in larger size and more clearly than could be possible were the entire elevation attempted. Fig. 2 is a side elevation with a portion broken away. Fig. 45 3 is a plan view of the upper part of the machine. Fig. 4 is a section of the upper part of the machine, made on the line $x-x$ in Fig. 3. Fig. 5 is a side view of a modification of the improvement in which the principles of 50 my invention are comprised. Fig. 6 is a sectional side view of such modification.

A, Figs. 1, 2, 5, and 6, is the base of the

machine, made in the usual manner for holding the anvil or fixed swage or die it is intended to support in proper relation with the drop-hammer B, each of which parts is provided with the usual or any approved attachments for holding the fixed die or swage in proper relation with the hammer and its die or swage, to insure the required precision in the application of the machine, the hammer 60 sliding on vertical guideways B', formed on or attached to uprights C', bolted to the base A in the usual manner.

C is the flexible band or strap which raises the hammer, and which is preferably made of 65 good leather belting, but is not limited to this material. The band, strap, or belt C extends upward and passes over a pulley, D, thence downward between the pulley D and another pulley, E, and is tightly clamped or gripped 70 between the pulleys D and E during the act of raising the hammer B, but released from the gripping action of these pulleys when the hammer drops by mechanism yet to be described. It is evident that during the act of 75 falling the hammer would, unless prevented by special mechanism, drag the strap over the surface of the pulley D in the opposite direction to the motion of the latter, and the friction produced by such dragging action would 80 greatly increase the destructive wear upon the strap, and, like a brake, more or less retard the fall of the hammer, and as the living force, or *vis viva*, of the hammer is a strict function of the velocity of its fall, increasing or diminishing as the square of said velocity, it requires but a slight diminution of the velocity 85 to notably reduce the effect of the blow. I will now describe the mechanism by which these defects are obviated. The prime driver 90 of the machine is the pulley F, Figs. 1, 2, 3, and 4, in the example herewith given in these figures, to which pulley power may be transmitted by an endless belt (not shown) from any driving-shaft; but, as will subsequently 95 appear, this arrangement may be modified without affecting the nature of my invention. I do not therefore limit myself to this precise mode of imparting prime motive power to the machine. The pulley F is keyed to a shaft, 100 G, which has fixed bearings at H, Figs. 3 and 4, in the example of my invention shown in

Figs. 1, 2, 3, and 4. On the end of the shaft G, opposite the pulley F, is a stout pinion, I, which meshes into a gear, J, keyed to the shaft K of the pulley D. The pulley D is keyed to the shaft K, and this shaft has its journal-bearings at L in the ends of rock-bars or levers M. The rock-bars or levers M are keyed to a rock-shaft, N, which has its journal-bearings in bosses O, formed upon or attached to the horizontal metal frame P, which forms a support for the pulleys, gears, shafts, levers, and other mechanism, and which may be supported by hangers Q, attached to the overhead beams of a shop or building, or in any other suitable way supported in proper relation with the base A and its attachments. The rock-levers M are levers of the third order, or, being keyed to the shaft N, which acts as a fulcrum common to both of them and moving together for the same object, they may be regarded as forming a single lever of the third order, their purpose being to move the pulley D slightly toward or away from the pulley E, to effect the clamping or gripping of the band C between said pulleys or to release the band from such engagement, according as the lever or levers M are actuated by mechanism yet to be described. The lever or levers M are actuated by strong links R, pivoted to the levers M at about their middle, as shown at S. These links are bifurcated at the upper ends, where they are pivoted to the levers M, and at their lower ends they are fitted to small but strong eccentrics T, Figs. 2 and 4, which latter, when turned on their axes, actuate the links R, which, in their turn, apply power to the levers M, between their common fulcrum N, to overcome the resistance at the pulley-shaft K arising from the inertia and weight of the said pulley and its attachments, the friction of bearings, &c., when said pulley is moved toward or away from the pulley E for the purpose of gripping or releasing the band, strap, or belt C, as hereinbefore set forth. The eccentrics T are keyed fast to a rock-shaft, U, Figs. 2 and 4, which has its journal-bearings in the frame P. To the rock-shaft U is also keyed a lever, V, Figs. 2, 3, and 4, by which the shafts U and eccentrics T are turned radially on their common axis whenever the lever is moved upward or downward. To the end of the lever V remote from the shaft U is pivoted a tappet-rod, W. Formed as an integral part of or bolted to the hammer or drop B is an arm, X, Figs. 1, 2, and 4, having a hole in its outer extremity, through which the tappet-rod W passes, and when the machine is in operation the arm X freely slides up and down on the tappet-rod. Rigidly clamped to the tappet-rod W by clamping-screws y are adjustable tappets Y, against which the arm X strikes, the upper tappet being struck on the under side when the hammer B rises, and the lower one being struck on the upper side when the hammer is dropped, the tappet-rod being thus alternately raised and forced downward to actuate the mechan-

ism for clamping the band or strap C between the pulleys D and E. It will now be plain that when the drop-hammer B descends till the arm X strikes the lower of the two tappets Y the tappet-rod W will be forced downward by the impact, pulling with it the end of the lever V and causing the shaft U to rotate slightly on its axis, this motion, however, being only a small part of an entire revolution. The eccentrics T, keyed to the shaft U, share this motion, and through the links R, pivoted to the levers M, impart to said levers and the pulley D a slight radial movement toward the pulley E, the center of this radial movement being the center of the shaft N. This movement, though slight, is sufficient to tightly and firmly clamp the band or strap C between said pulleys, and the reverse movement, caused by the arm X striking the upper tappet, at once releases the strap from the clamping action of the pulleys. The pulleys are geared together in such manner that their circumferential motion is equal, and, as indicated by the arrows, the direction of their motion is such that when the strap is clamped, as described, between them their holding force, together with the friction of the strap on the pulley D, is sufficient to raise the hammer B without the slipping of the belt, thus insuring a positive and certain action of the machine. In order now that when the tappet-rod is raised or lowered for clamping or unclamping the strap between the pulleys D and E it shall with certainty retain either of the positions named until it is required to take the other position, I make use of the following device: To the frame P are bolted at their lower ends two strong arches, Z, these arches being primarily for the support of other mechanism hereinafter described. To the side of that one of these arches nearest the tappet-rod W, I pivot at a the brake-bar b, Figs. 1, 2, and 4. Abutting against the back of the brake-bar b is a spring, c, which forcibly presses said brake-bar against the convex end of the lever V. It will be seen that in passing either upward or downward the convex end of the lever V must press the brake-bar b back against the action of the spring c, the brake-bar being thus made to resist the lever until such time as the end of said lever passes the horizontal position, and that this resistance to the motion of said lever will keep the latter, and the tappet-rod connected with it, from moving by their own weight or by the jarring action of the machine until the action of the arm X upon the tappet Y changes the positions of all the correlated parts employed for clamping the strap between the pulleys D and E and releasing the strap from such clamping action; but while I have thus described the particular construction and action of a spring-brake for holding the lever V in position till the arm X engages one or other of the tappets Y, I do not confine myself to this precise construction, as other methods of constructing, attaching, and applying a spring-

brake may be used without at all affecting the principle of my invention.

The principal object of the arches *Z* is to afford bearings for certain counterpoised rock-levers, with idler-pulleys at one end, which, when the strap or band *C* is released from the clamping action of the pulleys *D* and *E*, raise the belt from the surface of these pulleys to prevent the frictional resistance of the strap from retarding the fall of the hammer and from rapidly wearing out the strap. I do not, however, confine myself to the particular method, which I shall presently describe, for actuating the idler-pulleys. The method shown is a preferable way of accomplishing the object sought; but the arrangement of the pulleys and their action remaining the same any other method of actuating them radially outward against the strap would be substantially carrying out the principles of my invention.

To the arched supports *Z* are attached horizontal round bars or shafts *d*, Figs. 1, 2, 3, and 4, which act as fulcrum-bearings for rock-levers *e*, counterpoised at the ends of their outer arms, as shown at *f*. The levers *e* are fitted to turn on the round bars or shafts *d*, and their arms opposite the counterpoised arms have at their extremities idler pulleys *g*, pivoted to the arms, as shown. These idler-pulleys have flanges *i* projecting from their rims at the outside to guide and retain the strap or belt *C* always in proper relation with their faces and the face of the pulley *D*. The strap or band *C* is made considerably broader than the face of the pulley *D*, as shown in Figs. 1 and 4, projecting equally over each side of the rim of the pulley *D*, and the faces of the rims of the idler-pulleys *g* inside of the flanges *i* are just broad enough to occupy and extend across the portions of the strap *C*, which project laterally over the pulleys *D*. The pulleys *g'*, Figs. 2 and 3, are constructed with flanges like the pulleys *g*, but their diameters are less. They are pivoted to the counterpoised rock-lever *e* at its inner end, as shown, one above and one below the strap, where the latter passes between the clamping-pulleys *D* and *E*. The idler-pulleys *g'* act as guides for the strap *C* to hold the latter always in proper relation with said clamping or gripping pulleys, and the lower of these two idlers acts also to hold the strap away from the perimeter of *E* when the drop-hammer *B* is effecting its blow, and, as aforesaid, I consider any substitution of springs for the counterpoised rock-levers, or of weights acting through other mechanism upon the idler-pulleys to move the same outward against the strap, band, or belt as an equivalent of the counterpoised rock-shaft herein described as a means for effecting such movement.

Figs. 5 and 6 represent a modification of the invention, which, however, carries out the principles above enunciated, to wit, the clamping of a flexible band, strap, or belt between

a pulley having fixed bearings and a pulley having movable bearings, an arrangement of idler-pulleys in relation with a pulley having fixed bearings and a pulley having movable 70 bearings, to relieve said flexible strap, band, or belt from friction on the surfaces of the clamping-pulleys during the fall of the drop-hammer, substantially as hereinbefore specified. In this modification the pulley *E'* is the one 75 provided with movable bearings in the end of the rock-lever *e''*, and the counterpoise *g''*, or an equivalent, acts upon the end of said rock-lever opposite the pulley *E'* to press the pulley *E'* toward the pulley *D'*, for clamping the 80 strap, band, or belt between said pulleys for raising the hammer *B*. In this example of my invention the driving-pulley *F'* is keyed directly to the shaft *K* of the pulley *D'* without intermediate gearing. The arrangement 85 of counterpoised levers and flanged pulleys *e'g* is substantially the same and for the same purposes as hereinbefore set forth in the example of the invention shown in Figs. 1, 2, 3, and 4. The release of the strap, band, or belt 90 from its engagement by the gripping or clamping action of the pulleys *D'* and *E'* is effected in this modification, as in the example already described, primarily by the action of the arm *X* projecting from the hammer *B* upon the 95 tappets *Y* or the tappet-rod *W*; but there is a slight change in the mechanism by which the vertical upward and downward movement of the tappet-rod finally effects the alternate clamping and release of the strap, as follows: 100 The upper end of the tappet-rod *W*, Figs. 5 and 6, is formed with an enlargement, *k*. This enlargement is recessed in the upper part to form a socket, *l*, for the reception, retention, and support of a spring, *m*. The end of the rock-lever *e''* is flattened on the under side at *n*, or otherwise suitably adapted to the spring *m*. At *o*, where the enlarged portion *k* of the rod joins and is continuous with the lower part of the same, is an easy fillet, which, when the 105 machine is in action, acts against the lower end of the brake-bar *b'*, which is pivoted to the side of one of the metallic arches *Z* in the same way as in the example of the invention shown in Figs. 1, 2, 3, and 4. This 110 brake-bar has a function strictly analogous to that in Figs. 1, 2, 3, and 4, which is to hold up the tappet-rod when raised till the hammer has made its blow, in doing which the arm *X* acts upon the lower tappet on said rod 115 to pull the tappet downward. The downward motion of the tappet-rod brings the fillet *o* into action against the inwardly-curved end of the brake-bar *b* and forces the latter outward against the pressure of the spring *e'*, which 120 spring is therefore in function, also the analogue of the spring *e* in Figs. 1, 2, 3, and 4. The brake-bar *b'* has on its inner side a shoulder, *r*, which engages the under side of the end of the lever *e''* to hold it up against the 125 weight of *j'*, or an equivalent, when raised by the upward movement of the tappet-rod. The 130

spring *m* acts in this modification as a buffer to prevent shock between the rock-lever *e'* and the upper end of the tappet-rod.

In either way of carrying out the invention 5 the tappet-rod may be worked by hand-levers *L*, as indicated in Figs. 5 and 6. It will now be apparent that in action the band, strap, or belt will have frictional contact or engagement with the perimeters of the pulleys *D* and 10 *E* only when the hammer or drop is being raised, during which time said strap will be tightly clamped and held from slipping on said perimeters, and that when the hammer begins to fall the belt will be supported by the 15 pulleys *g* or *g'* and *E'*, and instead of slipping over the surfaces of *D* and *E* in an opposite direction to the motion of the latter, thus to cause wear of the strap and frictional resistance to the descent of the hammer, the pulleys *g* or *g'* and *E'* will turn freely on their axes and obviate such wear and resistance.

In the counterpoise *f* of the counterpoised lever *e'*, which has at the opposite end the idler-pulleys *g* and *g'*, at the point where the pulley 25 *E* presses the strap *C* against the pulley *D* for clamping or gripping said strap, is an adjustable set-screw *y'*, Figs. 2 and 3, which abuts against a stop, *w*, affixed to the frame *P*, by the adjustment of which the fall of this rock- 30 lever is regulated to the exact distance necessary to keep the strap at this point from coming into frictional contact with the pulley *D* during the fall of hammer, which contact might otherwise be caused by the counterpoise *f* 35 falling too far.

Having thus fully described my improvement, what I claim as my invention, and desire to secure by Letters Patent, is as follows:

1. In a drop-hammer, the combination, with 40 a hoisting-pulley and hammer-head, of a belt attached to said hammer-head and passing over said pulley, and a series of idler-pulleys or rollers for taking the belt off the hoisting-pulley preparatory to the fall of the hammer-head, whereby the loss of velocity due to friction is materially diminished and the force of the blow consequently increased, substantially as set forth.

2. The combination, with the hoisting-pulley and hammer-head, of a drop-hammer and a belt attached to the hammer-head and passing over the hoisting-pulley, of a gripping or clutch pulley for engaging said belt with said hoisting-pulley, and movable idler-pulleys or 55 rollers for taking the belt off the hoisting-pulley preparatory to the fall of the hammer, substantially as and for the purposes described.

3. The combination, with the hoisting-pulley and hammer-head in a drop-hammer, of a 60 hoisting-belt wider than the face of said hoisting-pulley, and flanged idler-pulleys or rollers engaging the overhanging edges of said belt for disengaging said belt from the hoisting-pulley preparatory to the fall of the hammer, 65 substantially as and for the purposes set forth.

4. In a drop-hammer or drop-press, the com-

bination of a hoisting-pulley, a belt passing over the hoisting-pulley and attached to said hammer-head, a friction or gripping roller or pulley, and mechanism operated by the hammer-head for effecting the gripping action of the friction-roller and hoisting-pulley, with a series of idler-pulleys for engaging the edges of the belt and lifting the belt off the hoisting-pulley preparatory to the fall of the hammer-head, substantially as and for the purposes specified.

5. In a drop-press or drop-hammer, the combination, with a flexible strap, band, or belt for raising the hammer, and clamping-pulleys 70 narrower than such belt, one of which is a driving-pulley having fixed bearings, the other having movable bearings for clamping such belt between said pulleys when the face of one of the pulleys is pressed toward the face of the other, of idler-pulleys arranged in relation with said clamping-pulleys, and provided with movable bearings actuated by weights or their equivalent in such manner as to press said idler-pulleys outward against the inside faces 75 of the margins of said strap, band, or belt, which project laterally over the perimeter of the clamping-pulleys for receiving the weight of such strap, band, or belt, and relieving it from frictional contact or engagement with 80 said perimeter while the hammer or strap falls, substantially as and for the purpose specified.

6. The combination, with clamping-pulleys, one having fixed and another having movable 85 bearings for alternately clamping and releasing the strap, band, or belt which raises the hammer of a drop-press, of a strap, band, or belt broader than the clamping-pulleys, and idler-pulleys having movable bearings arranged in relation with said clamping-pulleys, 90 said idler-pulleys being actuated by weights or their equivalent for pressing said strap, band, or belt away from the faces of the clamping-pulleys when the hammer is falling, and provided with flanges for guiding said strap, band, or belt in proper relation with the clamping and idler pulleys, substantially as and for the 95 purposes described.

7. The combination, with clamping-pulleys, one having fixed bearings and another having 105 movable bearings for alternately clamping or gripping the strap, band, or belt of the hammer of a drop-press, of a lever of the third order having the movable bearings of one of the 110 clamping-pulleys at one extremity, and the fulcrum bearing or bearings at the other extremity, of such lever, a link-bar pivoted to said lever between said fulcrum-bearing and 115 said movable bearings of the clamping-pulley, an eccentric with fixed bearings fitted to a movable bearing in the other end of said link-bar, and a lever rigidly connected at one end to said eccentric and having its other end pivoted to a tappet-rod for actuating said eccentric, link-bar levers, and movable pulley 120 in clamping and releasing such strap, band, or 125 pulley.

130

belt, substantially as and for the purposes specified.

8. The combination of the pulley E, having fixed journal-bearings, the pulley D, having 5 movable journal-bearings, the lever or levers M of the third order having the movable bearings of the pulley D at one end and a fulcrum bearing or bearings at the other end, a link-bar R, pivoted to the lever or levers M 10 between the fulcrum bearing or bearings of said lever and the movable bearings of the pulley D, an eccentric T, having fixed bearings and fitted to a movable bearing in the end of said link-bar, not pivoted to the lever 15 M, a lever V, rigidly attached to the eccentric T at one end, the tappet-rod W, pivoted to the other end of the lever V, and the spring brake-bar b, pivoted to a support in relation with the end of the lever V, for holding the lever V and the parts connected with it when moved by said tappet-rod in a fixed position till again moved by the tappet-rod, substantially as and for the purposes specified.

9. The combination, with clamping or gripping pulleys, one having fixed and the other movable journal-bearings, a band, strap, or belt wider than said pulleys, attached to the drop or hammer of a drop-press, passing between said pulleys, for alternately lifting and 20 dropping said hammer, and mechanism for effecting approach and retreat of the face of

the pulley having movable journal-bearings toward or away from the pulley having fixed bearings for alternate clamping and release of said strap, band, or belt, of a series of idler-pulleys arranged in relation with the clamping-pulleys in a manner to bear against the inside of the margins of said strap, band, or belt, which project laterally over the faces of the clamping-pulleys, and counterpoised rock-levers for pressing said idler-pulleys out against the inside of the projecting margins of the strap, constructed and operating substantially as herein described, and for the purposes specified.

10. The combination of the strap C, attached to the hammer or drop B, lever V, eccentric T, link-bar R, rock lever or levers M, movable clamping-pulley D, pulley E, and the gears I and J, for causing the faces of the pulleys D and E to move with equal circumferential velocity, substantially as and for the purpose set forth.

11. The combination, with the rock-lever e', of the set-screw y', and stop w', for limiting the movement of said lever, substantially as and for the purpose specified.

FRANK M. LEAVITT.
